BUILDING FRONT

Edward Louis Mejer, 408 N. Lafayette Blvd.,
South Bend, Ind. 46601

Filed July 12, 1968, Ser. No. 12,725

Term of patent 14 years

Int. Cl. D25—04

U.S. Cl. D13—1

Fig. 1

FIG. 1 is a front elevational view showing my new design.

FIG. 2 is a view in side elevation showing my new design.

The characteristic features of my design reside in the portions shown in full lines as shown, it being understood, however, that the broken line disclosure in FIG. 1 constitutes a part of the claim. The broken line showing of the building in FIG. 2 is for illustrative purposes only.

I claim:

The ornamental design for a building front, as shown and described.
